US00D600907S

(12) United States Design Patent
Boyd et al.

(10) Patent No.: US D600,907 S
(45) Date of Patent:  Sep. 29, 2009

(54) PHONE CASE

(75) Inventors: Michael Boyd, Boulder, CO (US);
Richard N. Case, Boulder, CO (US);
Bowden Ormsbee, Longmont, CO (US);
Richard Schmelzer, Boulder, CO (US)

(73) Assignee: Crocs, Inc., Niwot, CO (US)

() Term: 14 Years

(21) Appl. No.: 29/303,882

(22) Filed: Feb. 19, 2008

(51) LOC (9) Cl. 03-01

(52) U.S. Cl. D3/218

(58) Field of Classification Search D3/218,

D3/219, 207-212, 215; 224/930, 666, 674,

224/219, 222, 267; D2/923-936; 379/453-455

See application file for complete search history.
